BRAUN TUBE

Manfred von Ardenne, Berlin, Germany, assignor
to Radioaktiengesellschaft D. S. Loewe, Berlin-
Steglitz, Germany, a company of Germany

Application March 6, 1933, Serial No. 659,617
In Germany March 7, 1932

2 Claims. (Cl. 250—27.5)

It is known in the case of television receivers to employ symmetrical Braun tubes, and to make use of line and image tilting potentials, which are necessary for scanning purposes, of different amplitudes, in order to obtain the well-known rectangular size. For producing the necessary tilting potentials of different amplitude it is necessary in arrangements of this kind to employ different tilting units. This results in a relatively complicated embodiment of the arrangement, which acts in disturbing fashion, particularly in the matter of dimensioning and also as regards any new parts which may be required.

The subject matter of the invention is an arrangement which does not reveal the disadvantages referred to.

According to the invention, line and image potentials of the same amplitude are employed. The difference in the lateral dimensions of the resulting picture is obtained by corresponding adaptation of the sensitiveness of the pairs of control plates. The sensitiveness of the pairs of control plates may be varied as required by corresponding selection of the distances between the plates and by choice of the points of deflection, and also by corresponding selection of the size of the plates. The size across usual at the present time may be accomplished, for example, by making the spacing of the one pair of plates equal to 5 mm., and that of the other pair of plates equal to 8 mm. The same result may also be obtained by making the length of the one pair of plates 20 mm., and that of the other pair 30 mm.

Naturally, these statements represent merely examples of possible forms of embodiment. The essential feature of the invention is merely the use of tilting potentials of the same amplitude and deflecting plates of different sensitiveness.

Two forms of embodiment of the invention are illustrated by way of example in the drawing.

Fig. 1 shows an arrangement, in which the intermediate spaces 2 and 4 between the pairs of plates 1 and 3 are of different size. The distances 2 and 4 may be, for example, as 5:8. 10 is the cathode, 12 the anode and 13 the fluorescent screen; 11 is an electrode for controlling and concentrating the cathode ray. 14 and 15 are two deflecting voltage generators supplying the deflecting systems 1 and 3 with the deflecting

Fig. 2 shows an arrangement, in which the plates of the two pairs 1 and 3 possess different lengths 5 and 6. For example, 5 may possess a length of 20 mm., and 6 a length of 30 mm.

Naturally it is quite readily possible to make 5 the plates or the spacing of other size. It is also possible to utilize several measures at the same time.

According to the invention the tube, in order to fix definitely on the transverse size, is socketed 10 accordingly, for example is furnished with a base not capable of being exchanged, in such fashion that the unsymmetrical tube according to the invention may be operated only in the correct position, i. e., only in one of the two preferred 15 directions. Naturally the use of corresponding mountings incapable of being exchanged, and fitted in the correct position, is essential for the purpose of the invention.

Fig. 3 shows a television arrangement, wherein 20 a Braun tube, which may preferably show a form of embodiment according to Fig. 1 or 2, is arranged in an exactly defined correct position.

By reference to Fig. 3 of the drawing it will be seen that the tube 1 with the socket 8 is inex- 25 changeably held in the holder 9. The socket 1 in the holder 8 is constructed in such a manner that the deflecting plates of the tube have an exactly defined position, when the tube is mounted in the holder. The holder itself may be 30 mounted in any adapted manner.

I claim:

1. A Braun tube for television purposes comprising a cathode, an anode, means to control the cathode ray, means to concentrate a cathode ray 35 and a fluorescent screen, two pairs of deflecting plates, the distance between the plates of the first pair standing in the ratio of approximately 5:8 to the distance between the plates of the second pair. 40

2. A Braun tube for television purposes comprising a cathode, an anode, means to control the cathode ray, means to concentrate a cathode ray and a fluorescent screen, two pairs of deflecting plates mounted between said anode and 45 said fluorescent screen, the spacing of the plates of the one pair amounting to nearly 5 mm., and that of the other pair to nearly 8 mm.
